UNITED STATES PATENT OFFICE.

WALTER L. FORWARD, OF WEST BERKELEY, CALIFORNIA, ASSIGNOR TO BYRON JACKSON IRON WORKS, OF WEST BERKELEY, CALIFORNIA, A CORPORATION OF CALIFORNIA.

HIGH-PRESSURE TURBINE-PUMP.

964,963.

Specification of Letters Patent. Patented July 19, 1910.

Application filed March 9, 1910. Serial No. 548,149.

To all whom it may concern:

Be it known that I, WALTER L. FORWARD, a citizen of United States, residing at West Berkeley, in the county of Alameda and State of California, have invented new and useful Improvements in High-Pressure Turbine-Pumps, of which the following is a specification.

My invention relates to rotary high pressure turbine pumps, and particularly to a method of packing the guide vanes which are placed in the throat surrounding the runner.

My invention consists in the parts and the construction and combination of parts which will be more fully explained by reference to the accompanying drawings, in which—

Figure 1 is a general view of a multiple stage pump, showing the application of my invention. Fig. 2 is an end view showing the guide vanes and segments. Figs. 3 and 4 are sections showing the undercut grooves, and the packing material therein. Figs. 5, 6 and 7 show the dove-tailed form of said grooves. Fig. 8 shows a ring with beveled or chamfered locking section.

In a former application Serial Number 536,089, filed by me Jan. 3, '10, I have shown separable guide vanes located between the side walls and covers of the subjoined shells of the pump casing, and counterbores or grooves formed in said walls, with segments projecting from the vanes and fitting into said counterbores to secure the vanes in place.

My present invention consists in a means for more perfectly packing these segments where they fit into the counterbores.

A represents the guide vanes having the segments 2 formed upon the sides, said segments being of such length that when fitted into the circular grooves, channels or counterbores in the shells or covers, they form complete rings, and as they are formed integral with the guide vanes A, it will be seen that they hold these vanes in their proper relative position, at the same time allowing them to be readily removed and replaced independently of each other whenever desired or necessary; the parts being secured by bolts extending through holes 3 made in the guide vanes and in line with similar holes in the casing through which bolts pass for the purpose.

In my invention I make the grooves or channels 4 in which the segments 2 project of a width greater than the width of the segments, and also having a greater depth. These grooves or channels are preferably undercut or beveled inwardly as shown in the drawings, and they are filled with a packing of metal sufficiently fusible, which is cast in around the segments, thus forming an extremely tight joint at this point.

In Figs. 5 and 7 I have shown a section at the point where the groove or channel has a pocket 5 made deeper than the inner portion of the groove or channel. These pockets are located at intervals around the grooves or channels, and serve to retain the metal and prevent its slipping or turning independently of the part with which it is connected.

In Fig. 8 I have shown a segment 2 having a beveled, inclined or chamfered section 2^a into which the packing metal will flow, and by thus overlapping the ring at these points, the segments will be prevented from slipping, or being pulled out of place.

I do not broadly claim in this application the guide vanes with segments projecting from the vanes and fitting into counterbores formed in the walls of the casing, as the same forms the subject matter of my former application, Ser. No. 536,089, herein referred to.

Having thus described my invention, what I claim and desire to secure by Letters Patent is—

1. In combination, with the guide vanes of a turbine pump, and annular retaining segments formed thereon, of walls or covers having corresponding grooves adapted to receive the segments, and a lining of fusible metal cast therein.

2. In combination with a turbine pump, the guide vanes forming fluid passages therein and having outwardly projecting segments, of shells and covers having corresponding annular grooves into which the segments project, said grooves being undercut or beveled, and a filling of fusible packing metal cast into the grooves around the segments.

3. In combination with a turbine pump, the guide vanes forming fluid passages therein and having outwardly projecting segments, of shells and covers having corresponding annular grooves into which the

segments project, said grooves being undercut and having depressed pockets at intervals; and a filling of fusible packing metal cast into the grooves around the segments.

5 4. In combination with the guide vanes of a turbine pump, and annular retaining segments formed thereon, of walls or covers having corresponding grooves adapted to receive the segments and a lining of fusible metal cast therein, said segments having

beveled or chamfered sections to interlock with the lining metal.

In testimony whereof I have hereunto set my hand in the presence of two subscribing witnesses.

WALTER L. FORWARD.
